SPRAYER

Joseph W. Patterson, Tulsa, Okla., assignor to
 J. A. Vaughan Mfg. Company, Tulsa, Okla., a
 corporation of Delaware

Application November 4, 1933, Serial No. 696,646

10 Claims. (Cl. 299—89)

This invention relates to new and useful improvements in sprayers.

This application is filed as an improvement over the sprayer shown in my co-pending application filed January 28, 1933, Serial No. 653,987.

One object of the invention is to provide an improved sprayer of the continuous spray type for spraying various liquids, such as insecticides, paints and lacquers, as well as oil and other fluids.

10 An important object of the invention is to eliminate the spring clip for holding the eduction tube in the sprayer head shown in my co-pending application, whereby the manufacture of the sprayer head is greatly simplified and cost reduced.

Still another object of the invention is to provide a removable atomizing or eduction tube which is so constructed as to be readily and effectively mounted in a sprayer and held therein by its own resiliency and by its functional engagement with the head of the sprayer, whereby no outside medium is employed to hold the tube in position. An important object of the invention is to provide an eduction tube so bent as to engage at one end within the nozzle at one end of the head, and at an intermediate point to engage and fasten in the opening between the head and the liquid receptacle, whereby the tube is removably secured in the head with its leg directed downwardly into the receptacle.

A construction designed to carry out the invention will be hereinafter described, together with other features of the invention.

The invention will be more readily understood from a reading of the following specification and by reference to the accompanying drawing in which an example of the invention is shown, and wherein:

Figure 1 is a side elevation of a sprayer constructed in accordance with the invention.

Figure 2 is a longitudinal view of the same, partly in elevation and partly in section.

Figure 3 is an enlarged sectional view of the sprayer head.

Figure 4 is a vertical sectional view taken on the line 4—4 of Figure 3.

Figure 5 is a longitudinal sectional view of the sprayer head, and

Figure 6 is a detail of the eduction tube.

50 In the drawing the numeral 10 designates a sprayer barrel having a plunger 12 slidable therein. A plunger rod 13 has one end secured to the plunger and said rod is supported by and extends through a cap 14 which closes one end of the barrel. A suitable handle 15 is fastened on the

outer end of the rod for operating the plunger. Although I have shown a manually operated sprayer, it is to be understood that the invention is not to be limited to this particular type.

5 A cylindrical head 16, preferably made of brass, or other non-rusting or non-corrodible metal, is provided with an integral collar 17 at its rear end. Although it is preferable to make the head of non-rusting or non-corrodible metal, it is to be understood that it can be made of any suitable material. The collar 17 is offset to form an internal shoulder 18. This collar is adapted to fit around the forward end of the barrel 10 (Figures 2 and 3) and may be soldered, or in any other suitable way secured thereto. A disk 19, which separates the 15 interior of the barrel from the head, is confined between the shoulder 18 and the forward end of the barrel.

The forward end of the head is tapered to form 20 a conical nozzle 20. An opening 20' in the end 25 of the nozzle communicates with the interior of the head. It is noted that the opening in the end of the nozzle is substantially small in proportion to the size of the interior of the head 16. A suitable container, or receptacle, 21 for receiving the liquid to be sprayed is provided with an externally screw-threaded collar or neck 22. A cap 23 is adapted to screw onto the neck of the container to cover the same. A suitable packing gasket 24 is interposed between the upper 30 edge of the neck and the cap.

The cap is provided with a diametrical sump 25 in its top. The sump conforms to the contour of the cylindrical head 16 and the head is positioned 35 within said sump and is soldered, or in any other way suitably secured thereto, whereby the cap is permanently fastened to the underside of the head. The cap has an opening 26 in its top which registers with an opening 27 in the head when the cap is secured thereto, as is clearly shown in Figure 3. Thus, the openings 26 and 27 provide a communication between the head 16 and the container 21.

An atomizing or eduction tube 28, preferably 45 made of non-rusting or non-corrodible metal, is removably mounted within the head and has its tip 28' resting against the inner wall of the nozzle 20 at the center thereof. The particular construction of this nozzle is an important feature of the invention and is clearly shown in Figures 2 50 and 3. The tip 28' of the tube engages axially in the nozzle 20 and surrounds the opening 20'. The tube is bent upwardly and inclined rearwardly from its tip to conform to the nozzle and the tapered forward end of the head 16, and is then 55

bent rearwardly to form a horizontal portion 29 which engages the inside of the top of the head 16 and lies therealong. At the rear end of the horizontal portion 29, the tube is bent upon itself at substantially a right angle, whereby a vertical or upright leg 30 is formed.

The vertical leg depends through the openings 26 and 27 in the cap and head respectively, into the container 21. A forward offset bend or crook 31 is provided in the vertical leg 30 and when the tube is in position in the head 16 the lower portion of this crook frictionally engages the rear edges of narrow slots 26' and 27' extending rearwardly from the opening 26 and 27. Thus it will be seen that the tube is held in position within the head and container by the engagement of the crook 31 in the slots, together with the contact of the horizontal portion 29 of the tube with the top of the head and the resting of the tip 28' in the nozzle 20.

The lower end of the upright leg 30 of the tube extends into the container 21, which carries the liquid to be sprayed. It is noted that the tube terminates short of the bottom of the container and does not rest thereon, but is supported by the engagement of the offset crook 31 in the slots 26' and 27'. It is seen that the tube forms a direct communication between the container 21 and the outlet nozzle 20.

In Figure 3 the tube 28 is shown in position in the sprayer head. When it is desired to remove the tube, it is merely necessary to unscrew the container 21 from the head 16. The lower end of the vertical leg 30 of the tube is then swung forwardly in a short arc, which action will disengage the offset crook 31 from the slots 26' and 27'. The tube is then pulled downwardly and readily removed from the head 16 through the openings 26 and 27.

In replacing the tube, the tip 28' thereof is entered into the head through the openings 26 and 27. The tip is positioned to rest within the nozzle 20 and an upward movement of the tube will cause the horizontal portion 29 of the tube to engage the top of the head 16. Then by swinging the leg 30 rearwardly the offset crook 31 will be engaged in the slots 26' and 27'. There is a certain amount of spring or resiliency in the tube and it is this resiliency that holds the tube rigidly in position. Longitudinal displacement of the tube is prevented by the tip 28' bearing against the inner side of the nozzle 20 and the engagement of the crook 31 in the slots 26' and 27'. Vertical displacement of said tube is prevented by the contacting of the horizontal portion 29 of the tube with the top of the head 16 and the engagement of the crook in the slots.

A small opening 32 is provided in the disk 19 near the upper end of the same. This opening is normally covered by a flap valve 33 which may be made of light metal, leather, rubber, or other suitable material. The flap valve is secured at its lower end to the disk within the head 16 by a rivet or brad 34, and the material of which it is made is substantial enough so that normally the flap valve will close the opening. By observing Figure 3 it is obvious that the flap valve will serve as a check valve, for air can pass from the barrel 11 into the head 16, but air in the head is prevented from entering the barrel.

The forward end of the atomizing or eduction tube 28 is provided with slots 29'. With the forward end of the tube in position against the inner wall of the nozzle 20, it is obvious that air escaping from the head must first pass the slots

29' and by varying the size of these slots, the amount of air emitting from the nozzle may be controlled.

In operation the forward stroke of the plunger 12 will force air from the barrel 11 through the opening 32 and into the head 16, the flap valve 33 being swung inwardly. Air in the head will pass downwardly through the openings 26 and 27 into the container 21 above the liquid. Thus, the only escape for the air from the head is through the slots 29' in the forward end of the eduction tube and out through the nozzle 20. The size of the head is such that a large air storage space is provided and since the opening in the nozzle is insufficient to allow all of the air forced into the head by one stroke of the plunger to escape, an air pressure is built up within the head 16 and in the container 21 above the liquid. Continued reciprocation of the plunger 12 will further build up the pressure whereby a continuous stream of air is ejected from the nozzle 20.

As the air pressure controls the amount of air emitting from the nozzle, it will also control the amount of fluid ejected through the tube, because the air pressure in the head 16 and in the container 21 will equalize itself. As the pressure is built up by continued reciprocation of the plunger 12, the air and liquid streams will be increased proportionately, thereby providing perfect atomization at all times.

By varying the size of the slots 29' in the forward end of the tube 28, it is possible to further control the air emitting from the nozzle. It has been found that in spraying liquids, such as gasoline, naphtha, and the like, which flow freely, a small amount of air will suffice for perfect atomization. However, in spraying liquids, such as paint, it is necessary, because of their heavier consistency, to provide more air to attain perfect atomization. Therefore, it is to be understood that the slots 29' are not to be limited to any particular size or shape, as they may be varied to obtain the best results.

The conical nozzle 20, besides forming a seat 45 to position the forward end of the eduction tube 28, allows any fluid which may collect within the nozzle to drain back into the head, thereby eliminating the ejection of drops of fluid after the sprayer has been operated. Also, the large air space around the end of the eduction tube prevents clogging of the opening of the nozzle. The engagement of the offset crook 31 in the slots 26' and 27', together with the engagement of the horizontal portion 29 with the top of the head 16 and the resting of the tip 28' in the nozzle 20, holds the tube 28 firmly in position but yet allows it to be easily removed or replaced.

Manufacturing costs have been reduced to a minimum as no machined parts are necessary. The head and nozzle are made of one piece which is a stamping and can be produced very cheaply. All parts vital to the operation of the device are made of non-rusting or non-corrodible material, thereby making for longer use. The operation is positive as there are no adjustments to be made.

The description which has been given recites more or less detail of a particular embodiment of the invention, which is set forth as new and useful, however, I desire it understood that the invention is not limited to such exact details of construction, because it is manifest that changes and modifications may be made within the scope of the appended claims without departing from the spirit of the invention.

What I claim and desire to secure by Letters Patent, is:

- 5 1. A sprayer comprising, a head provided with a forwardly directed conical portion terminating in a nozzle opening, a receptacle secured to said head, a passageway between said head and receptacle affording communication therebetween, means for supplying air to the head including a valve for building up air pressure within the head and nozzle, and an eduction tube provided with an opening adjacent one end of said tube for admitting air from the head into said tube, said tube being arranged in said sprayer with the end adjacent said aperture engaging in said nozzle opening and extending rearwardly therefrom through said passage-way into said receptacle with an intermediate portion of said tube in engagement with the wall of said passageway, said tube being so bent as to afford a resilient holding engagement with said nozzle and passage wall.
- 10 2. A sprayer comprising, an air pressure chamber having a nozzle at the forward end thereof, a liquid receptacle located beneath the air storage chamber, the chamber and receptacle having registering openings, a bent eduction tube open at each end and extending upwardly from the lower portion of the receptacle into the air pressure chamber and forwardly through the chamber to the nozzle, said tube having an upright leg provided with a forwardly offset crook which frictionally engages the upper edges of the registering openings to hold the tube in position.
- 15 3. A sprayer comprising, an air pressure chamber having a nozzle at the forward end thereof, the chamber having an opening in its bottom, a liquid receptacle located beneath the air storage chamber and having an opening in its top which registers with the opening in the chamber, the chamber and receptacle having slots which extend rearwardly from the openings, a bent eduction tube open at both ends and extending upwardly from the lower portion of the receptacle into the air pressure chamber and forwardly through the chamber to the nozzle, said tube having an upright leg provided with a forwardly offset crook which frictionally engages in the slots in said chamber and said receptacle, whereby the tube is held firmly in the position.
- 20 4. A sprayer comprising, a receptacle having an opening in its top, a hollow air storage head mounted on said receptacle and having an opening registering with the opening in the receptacle, the receptacle and head being provided with narrow slots extending rearwardly from the openings, a nozzle at the forward end of the head, means for closing the rear end of the head, means for supplying air under pressure to the head, a bent eduction tube open at each end extending from the lower portion of the receptacle through the head to the nozzle, said tube having an upright leg provided with an offset crook which frictionally engages in the slots in the head and receptacle to removably hold the forward end of the tube in engagement with the inner wall of the nozzle.
- 25 5. A sprayer comprising, a receptacle having an opening in its top, a hollow air storage head mounted on said receptacle and having an opening registering with the opening in the receptacle, the receptacle and head being provided with narrow slots extending rearwardly from the openings, a nozzle at the forward end of the head, means for closing the rear end of the head, means for supplying air under pressure to the head, a bent eduction tube open at each end extending

from the lower portion of the receptacle through the head to the nozzle, said tube having an upright leg provided with an offset crook which frictionally engages in the slots in the head and receptacle to removably hold the forward end of the tube in engagement with the inner wall of the nozzle, the tube having a side opening within the nozzle for admitting air under pressure from the head.

6. A sprayer comprising a horizontal cylindrical head with a passage-way in its lower side and a forwardly extending nozzle, and an eduction tube having a horizontal spray nozzle engaging end or tip and being bent upwardly and inclined rearwardly therefrom and then bent at such an angle that a horizontal portion is formed at the upper portion of the tube extending rearwardly and engaging with the upper portion of the spray head, the tube being bent downwardly upon itself at the rear end of said horizontal portion substantially at right angles and extending downwardly through said passage-way whereby an upright leg is formed, and said leg being provided with a forwardly extending off-set portion engaging with the lower portion of the head where it extends through said passage-way for holding the tube in operating position.

7. The combination with a sprayer head having a conical nozzle at one end and an opening in its bottom at its opposite end provided with a notch, of an eduction tube bent upon itself and removably mounted in the head, said tube having an upright leg extending through the opening of the head and engaging in the notch thereof and also having a forwardly directed tip engaging in the nozzle, whereby the tube is held in the head.

8. The combination with a sprayer head having a conical nozzle at one end and an opening in its bottom at its opposite end provided with a notch, of a resilient eduction tube bent upon itself and removably mounted in the head, said tube having an upright leg extending through the opening of the head and engaging in the notch thereof and also having a forwardly directed tip engaging in the nozzle, said tube also having an upwardly arched portion between its leg and tip in the head giving spring to the tube, whereby it is held in the nozzle and the notch.

9. In a sprayer comprising a sprayer head with a forward nozzle opening and a lower fluid receptacle, a passageway between the sprayer head and receptacle, an eduction tube having a tip engaging with the head at the nozzle opening, said tube extending rearwardly therefrom and bent downwardly providing a leg extending downwardly through the passageway and into the fluid receptacle, said leg bearing against the rear wall of said passageway, and the tube having a resilient portion between the tip and the point of engagement with the passageway so as to cooperate therewith and maintain it under stress in position.

10. In a sprayer comprising a sprayer head with a forward nozzle opening and a lower fluid receptacle, a passageway between the sprayer head and receptacle, an eduction tube having a tip engaging with the head at the nozzle opening, said tube extending rearwardly therefrom and bent downwardly providing a leg extending downwardly through the passageway into the fluid receptacle, and said tube being so bent and arranged in said head as to cause the tip to engage in said nozzle and the tube to engage another portion of the head and to be held under stress in the head by its own resiliency.
